CLAIM

I claim the ornamental design for an light fixture, as shown and described.

DESCRIPTION

FIG. 1 is a bottom perspective view of an light fixture showing the new design;

FIG. 2 is a top perspective view of the light fixture thereof;

FIG. 3 is a front elevation view of the light fixture thereof, which is identical to the left side elevation view, the right side elevation view, and the back side elevation view;

FIG. 4 is a bottom plan view of the light fixture thereof; and, FIG. 5 is a top plan view of the light fixture thereof.

The broken lines in the figures represent unclaimed portions of the light fixture and form no part of the claimed design.
